UNITED STATES PATENT OFFICE

ALLISTER S. MITCHELL, OF OAKLAND, CALIFORNIA, ASSIGNOR TO NATIONAL AUTOMOTIVE FIBRES, INC., OF DETROIT, MICHIGAN, A CORPORATION OF DELAWARE

UPHOLSTERY-MAKING MACHINE AND PROCESS

Application filed October 30, 1930. Serial No. 492,348.

This invention relates particularly to a machine and method for manufacturing stuffed, pleated upholstery. Such a machine is adapted, for example, to the manufacture of automobile seat-cushions, back-cushions, etc.

The primary object is to provide an improved machine and improved method which will greatly facilitate the manufacture of stuffed, pleated upholstery.

More especially, the present invention is intended to provide a machine particularly suited to the use of pre-cut covers in forming cushions, for example, for automobiles.

The objects of the invention are, in a large measure, accomplished by making use of the principle of fluid pressure (through the medium of a suction-carrier) for shaping the main (finish) fabric into pleat-fullnesses and intervening seam-ridges; and, preferably, important novel adjuncts are used in connection with the pneumatic carrier for shaping and feeding the materials through the machine and properly forming the upholstery.

In the use of the improved machine, as preferably constructed, pre-cut covers, a lining-fabric, and strips of batting are fed through the machine, the pre-cut covers being lowermost as the work is fed through the machine; the lining-fabric has formed therein upstanding seam-ridges; the pre-cut covers are fed, seriatim, over a suitable bed and provided with upstanding seam-ridges and intervening depressed pleats, or pipes, the seam-ridges of the covers becoming nested within the seam-ridges of the lining-fabric; the strips of cotton-batting, or the like, are drawn through with the fabrics and fill the pleats; and the upstanding, nested seam-ridges of the lining-fabric and of the pre-cut covers (suitably spaced) are sewed by means of sewing mechanisms mounted on a cross-beam above the path of the materials, each sewing-mechanism preferably comprising a head carrying a sewing-needle and looper-needle.

The work is fed continuously through the machine. The lining is a continuous fabric; the cotton batts are continuous strips; and the cover-fabric preferably is pre-cut to pro-

vide covers, which, in the operation of the machine are sewed to the lining. Preferably, the batts fed to the pleats are periodically broken to correspond with spaces between cushions, so that the upholstery produced is a continuous piece composed of a series of cushions connected by short lengths of lining-fabric. The lining-fabric may be cut at the spaces between cushions to effect separation of the cushions.

In the present invention, use is made of a suction-conveyor and associated spaced ridges in accordance with Mitchell U. S. application, Serial No. 427,205, filed February 10, 1930; and, for the purpose of adapting the machine to handle with great facility pre-cut covers, the present invention employs, in combination with the device mentioned, cover-placing mechanism adapted to position the covers, one at a time, over the conveyor and the ridges at the upper side of the conveyor, and co-acting depressing devices, or pleat-formers, which operate to depress linear portions of the cover into the spaces between the ridges and thus bring the cover fabric within the effective action of the suction conveyor. The seam-ridges of the cover are at the same time formed over the ridges associated with the conveyor. Preferably, the formers travel in cycles and are depressed progressively in pairs, first at the medial line of the machine and then in both directions laterally therefrom. The effect is to progressively pleat the cloth over the ridge-bars associated with the conveyor from the intermediate portion of the cloth laterally progressively in both directions.

The invention is illustrated in a preferred embodiment in the accompanying drawings, in which—

ken plan view illustrating the upholstery formed by the machine as comprising a series of cushions connected by the continuous lining-fabric; Fig. 27^a, a broken section on a reduced scale, taken as indicated at line 27^a of Fig. 25; and Fig. 27^b a reduced-scale section taken as indicated at line 27^b of Fig. 25.

Describing the preferred embodiment illustrated:—

A designates a main frame which is 75 equipped near its front end with a vertically adjustable cross-head A', the frame being provided with a bed-extension A² over which the covers are fed and being equipped with standards A³ which serve as a support for a conveyor frame A⁴ over which the cotton batts are fed; B (Fig. 4), a suction-conveyor device mounted in the bed of the machine; B', an auxiliary conveyor disposed back of the conveyor B; B², longitudinally extending ridge-bars extending over the conveyors; C, a series of sewing-mechanisms mounted on the cross-head A' and laterally adjustable thereon to enable the width of the pleats to be varied, said sewing-mechanisms being 80 actuated by a common shaft C', which, as shown in Fig. 3 is driven through the medium of a coupling shaft C² from a shaft C³ journaled in the main frame; D, a thread-supporting device carried by the cross-head A'; E, E', a pair of front feed rolls through which the upholstery is delivered from the machine, these rolls being actuated through the medium of change-speed gear mechanism E²; F, a forming-roll disposed back of and carried by the lower portion of the adjustable cross-head A', said forming-roll having spaced circumferential grooves through which the ridge-bars B² extend; G, a series 85 of lining-creasers adjustably mounted on a transverse bar G' carried by the bed; H, H' a main pair of batt-feeding rolls journaled in supports A⁵ carried by the bed; I, I' an auxiliary pair of batt-feeding rolls journaled in the members A⁵, these auxiliary rolls being periodically arrested to cause severance of the batts; J, a shearing device upon which the batts are severed when the rolls I and I' are stopped; K, a deflector-roll whose function is to direct the batts between the 90 rolls H and H' when the feed of the auxiliary rolls is resumed; L, (Figs. 1 and 2) an electric motor which actuates, through the medium of a chain or belt L', a counter-shaft L²; L³, a chain driven from shaft L² and serving to actuate a shaft L⁴ which forms a part of the gear mechanism E²; L⁵, a chain connecting the shaft L⁴ to a short parallel shaft L⁶, which, as shown in Fig. 2, serves to actuate the shaft-section C³ through the medium of which the shaft C' is driven to actuate the sewing-mechanisms; L⁷, (Fig. 2) a chain driven from the lower feed roll E and serving to actuate a shaft L⁸ which 95 actuates a chain L⁹ which operates the aux- 100

iliary batt-feeding rolls and the batt conveyor; L^{10} , a chain driven by the shaft L^8 which serves to actuate a cam-shaft L^{11} equipped with a cam L^{12} (Fig. 1) which 5 controls a clutch-lever L^{13} which periodical- 10 ly operates a clutch L^{14} which controls the driving of the chain L^9 from the shaft L^8 ; L^{15} , (Figs. 2 and 3) a chain driven from the front feed-roll E and serving to actuate a 15 shaft L^{16} , which, in turn, drives a chain L^{17} which actuates the suction-conveyor; L^{18} , a chain driven from the roll E and serving to drive a shaft L^{19} from which motion is 20 communicated through a gear-device L^{20} to the forming-roll F ; L^{21} , a chain driven by the shaft L^{19} and serving to actuate the main 25 batt-feeding rolls H and H' ; L^{22} a chain serving to drive the deflector-shaft K from the auxiliary batt-feeding roll I' ; M , (Figs. 1, 9 and 12) a feed-table upon which the 30 pre-cut covers are placed, seriatim, the covers being taken from a pile M' supported on a table M^2 ; N , (Figs. 1, 2, 9, 10, 12 and 17) cover-placing mechanism which operates 35 to advance the covers, one at a time, from the feed-table M to a position above the conveyors; O (Sheets 1, 2, 4, 6, 9 and 10), fabric-forming mechanism cooperating with the 40 suction-conveyor and associated ridge-bars in forming the covers into pleats and intervening seam-ridges; P , a lining-fabric which passes over a roll P' and thence to the forming-roll F ; and Q , strips of cotton bat- 45 tting supported by a conveyor Q' mounted on the frame-part A^4 , said conveyor being driven by a sprocket-chain Q^2 which is actuated by a shaft Q^3 driven by the sprocket-chain L^9 .

The shaft Q^3 also drives the lower auxiliary feed-roll I through the medium of an idler Q^4 , (Fig. 1).

The main frame of the machine may be of any suitable construction. In the illustration given, the bed-extension A^2 of the frame 45 is shown equipped with two conveyors, the front one of which is a suction-conveyor and the other one of which is without suction. However, the invention is not limited to such arrangement.

The suction-conveyor B may be adjustable to enable it to be raised or lowered slightly, if desired, for the purpose of enabling the depth of the pleats to be varied. This feature is illustrated in the above-mentioned application.

The suction-conveyor B is in the form of a belt mounted on front and rear rolls 1 and having its upper reach supported by rolls 2. The conveyor belt is driven by a drum 3 mounted on a shaft 3^a . The belt also passes about a drum 4 mounted on a shaft 4^a , as appears from Fig. 4.

Referring to Fig. 2, the sprocket-chain L^{17} engages a sprocket on the shaft 3^a and passes also about sprocket wheels on the shaft

4^a and on a shaft 1^a which forms an extension of the roll 1.

The suction-conveyor B has its upper length serving as a cover for a shallow pan 5, with the lower wall of which is connected a 70 suction-pipe 5^a , which leads (Fig. 1) to an exhaust fan 5^b driven by a motor 6. A moderate vacuum is maintained in the suction-conveyor. This is sufficient to cause the conveyor to grip the pleat-portions of the cover 75 and carry the cover forwardly to the sewing-mechanisms.

The rear or auxiliary conveyor B' is driven from the front conveyor through the the medium of gears 7, as appears in Fig. 21.

The ridge-bars B^2 extend longitudinally over both conveyors. They are adjustably secured at their front ends to a cross-bar 8 (Fig. 4), and at their rear ends to a cross-bar 9. It will be noted that the front conveyor 85 extends in front of the sewing-mechanisms, and the same is true of the ridge-bars. The ridge-bars register with the circumferential grooves of the forming-roll F and also with 90 grooves or spaces between adjustable shoes 10 with which the cross-head is equipped at its lower edge.

The seam-ridges of the cover-piece pass through the grooves just mentioned and are 95 nested within seam-ridges which are formed in the lining-fabric P , as the lining-fabric passes beneath the forming-roll F .

It will be understood that the ridge-bars B^2 are laterally adjustable on the cross-bars 100 8 and 9 to enable different widths of pleats to be formed.

The manner in which the ridge-bars extend through the grooves of the forming-roll and through the spaces between the shoes 10 105 carried by the cross-head, will be understood from Fig. 25. The ridges of the members B^2 are cut away, as indicated at 11 to enable the sewing-needles to be thrust transversely through the nested seam-ridges, it being understood that the ridges support the nested seam-ridges up to the point where the sewing-mechanisms operate upon the seam-ridges.

The sewing-mechanism C may be of any 115 suitable construction and operated in any suitable manner. The sewing-mechanisms shown (Figs. 3, 25 and 26) are the same as those shown in Mitchell U. S. application Serial No. 347,935, filed March 18, 1929 and need not be described in detail. Referring to Figs. 25 and 26, it may be stated, however, that the sewing-mechanisms are pivotally suspended from brackets 12 which are adjustably mounted on the cross-head A' , and that the actuating shaft C' is also journaled in said brackets. The sewing-needle is designated 13. It is actuated by a lever 13^a which swings in a transverse plane. The sewing-thread is designated 13^b.

The looper-needle is designated 14. It is actuated by a lever 14^a which swings in a plane parallel with the seam, and also rises and falls, so that the point-portion of the 5 looper-needle is carried in an elliptical path, the sewing-needle passing first above and then below the looper-needle. The looper-needle thread is designated 14^b.

As the fabrics move through the machine, 10 the lining-fabric P has formed therein U-shaped seam-ridges 15, and the cover-fabric M' has formed therein U-shaped seam-ridges 16 which become nested within the seam-ridges 15 as the fabrics pass beneath 15 the forming-roll F. The head of each sewing-mechanism is equipped with a depending seam-embracing shoe 17 which is provided with a perforation through which the sewing-needle may pass. In the sewing operation, 20 the sewing-needle passes through the nested seam-ridges; and the sewing-needle and looper-needle cooperate to produce a double thread chain-stitch. This feature forms no part of the present invention. 25 As shown in Fig. 27, the upholstery as it emerges from the machine consists of a series of connected cushions which are joined together simply by the lining-fabric at the spaces designated x.

30 The spool support D carried by the vertically adjustable cross-head A' supports the looper-needle spools 18 and the sewing-thread spools 19.

The front feed-rolls E and E' are connected by gears 20 (Fig. 3). The upper feed-roll is journaled in brackets 21 carried by a shaft 22 (Fig. 4) journaled in lugs 23. When desired, the roll E' may be drawn forwardly to a position shown in Fig. 1 to enable the 35 cushion materials to be introduced. The rolls preferably are covered with rubber, as indicated at 24. While the rolls E and E' are not an absolute essential, it is preferred to employ them. Ordinarily, they are geared 40 to run slightly faster than the suction-conveyor.

The forming roll F may be of any desired construction. Ordinarily, it comprises a shaft 25 equipped with laterally adjustable 45 collars 25^a, provided with circumferential grooves 25^b. The lateral adjustment of the collars is desirable to enable the pleat-width to be varied. The shoes 10 are also adjustably connected with the lower portion of 50 the cross-head A', as appears from Fig. 25.

As appears from Fig. 2, the roll P' over which the lining-fabric P passes is provided with laterally adjustable collars 26. These collars preferably are spaced to correspond 55 with the grooves of the forming-roll F and operate to produce initial seam-ridges in the lining-fabric, which persist more or less until the forming-roll is reached. The lining-fabric then passes over the creasers G (Figs. 1, 2, 4 and 25). These creasers

have flaring or V-shaped bases which are spaced slightly above the ridge-bars B^a (Fig. 27^a).

When the forming-roll is in the operative position shown in Fig. 25, the creasers extend into the grooves of the forming-roll, so that the lining is properly provided with seam-ridges; and the seam-ridges of the cover M' become nested within the seam-ridges of the lining, as the two fabrics pass beneath the forming-roll.

As will be understood from Figs. 25 and 27^b, the shoes or lining-creasers G are provided with upwardly and rearwardly inclined arms, or portions, 26^a, over which the seam-ridges of the lining-fabric are pre-formed during the passage of the lining from the roll P'. The intermediate formers G extend highest, and the flanking formers are progressively reduced in height, passing from the longitudinal central portion of the machine laterally towards the sides. The result is that the lining-fabric is first gathered on the upper ends of the longest arms 26^a, and then, progressively, upon the members of the flanking pairs.

From the description given, it will be understood that the upper extremities of the arms 26^a are arranged en echelon for the purpose of facilitating the gathering of the lining. It may be remarked that the preliminary gathering of the lining occurs when the lining passes over the collars 26 of the roll P'; but the final shaping of the seam-ridges of the lining is accomplished in passing over the arms 26^a and finally between the lower apex-portions 26^b of the shoes G, which project into the grooves 25^b.

As will be understood from Figs. 27^a and 27^b, the forming-device F preferably is 105 equipped with pinions or star-wheels 25^c which, in a sense, dig into the lining and cotton and effectively aid in feeding the material beneath the forming roll and past the sewing mechanism. These pinions are shown 110 mounted between the collars 25, but any suitable arrangement may be employed.

As appears from Fig. 25, the sewing head is adapted to swing about the axis C', it being observed that the brackets 12 are equipped with arms 12^a and the sewing heads are equipped with arms 17^a between which are confined springs 17^b mounted on rods 17^c which are pivotally connected at 12^b and which engage slots at the extremities of the arms 17^a. The construction permits very slight oscillation of the sewing head during the sewing action.

The main pair of batt-feeding rolls H and H' and the auxiliary pair of batt-feeding rolls I and I' are preferably fluted longitudinally as appears from Figs. 2 and 4.

The main batt-feeding rolls H and H' run continuously. The auxiliary batt-feeding rolls I and I' are periodically arrested to 130

cause the batts to be severed between cushion.

The drive chain L' is intermittently stopped, so as to stop the operation of the auxiliary batt-feed rolls I and I' and also the operation of the batt-conveyor Q' .

In Fig. 2, the batt-conveyor Q' is omitted. However, this figure shows the frame A^4 equipped with cross-members 27 with which 10 are connected laterally adjustable divider-strips 28 which are disposed just above the upper length of the conveyor Q' , the batts being fed between the divider strips from any suitable source of supply (not shown).

15 The batt-severing bar J (Figs. 2 and 4) is suitably notched to engage the strips of cotton. These notches act as shearing notches when the feed of the auxiliary rolls I and I' is stopped, while the feed of the main rolls H and H' is continued. When the rotation 20 of the rolls I and I' is resumed, the deflector-roll K operates to guide the batts to the main batt-feeding rolls H and H' .

25 The motor L which drives the various mechanisms and the numerous drive-chains connected thereby have already been described.

30 The feed-table M (Figs. 1, 9 and 12-16) is shown as consisting of a table or platform 29 equipped at its lateral edges with upstanding flanges 29^a ; a dark-colored cloth or fabric 30 supported on the table; a white pattern-like guide 31 supported on the dark background; and a glass plate 32 placed over the guide-pattern 31 and confined between the flanges 29^a of the table. The guide-pattern is provided with a center mark 31^a , and preferably is of substantially the form of the cover. It is provided near its front corners with recesses 31^b adapted to permit the grippers of the cover-placing mechanism to close upon the cover without catching the guide-pattern. The front margin of the guide-pattern projects in front of the front edge of the glass-plate 32 and is supported on laterally adjustable metal strips 33 carried by a slotted member 34 which is secured to the front edge of the table, as by screws 35. The plates or strips 33 are equipped at their rear margins with fixedly secured bolts 36 which depend through the slots in the members 34 and are equipped with wing nuts 36^a . The supporting strips 33, are provided, as shown in Fig. 16, with notches or recesses 33^a , which are 35 adapted to accommodate the grippers when they grip the cover. As indicated, the supporting strips 33 may be adjusted to vary the positions of the recesses 33^a when it is desired to vary the positions of the grippers laterally to handle covers of different widths.

30 The cover-placing mechanism N (Sheets 1, 2, 5, 6, 7 and 8) comprises, in the form shown, a pair of forwardly and rearwardly reciprocal gridders 37 adjustably carried by slides 38 which are mounted on tubular guides 39

supported at the sides of the bed of the machine; sprocket-chains 40 attached to the slides 38, the rear ends of the sprocket-chains being supported on sprocket wheels 41 as best shown in Fig. 12, and the front ends being supported on sprocket-wheels 42 mounted on a transversely extending shaft 43, as best shown in Figs. 17 and 18; a pair of frame-supported guide-bars 44 disposed beneath the paths of the slides 38 and engaged by depending extensions 38^a of said slides; a vertical actuating shaft 45 (Fig. 17) having its upper end geared to the shaft 43 and having its lower end provided with a swinging extension 45^a equipped with a friction wheel 45^b ; a shaft 46 equipped with friction-disks 47 and 48, either one of which may serve to actuate the disk 45^b ; a sprocket-chain 49 driven from the shaft L^2 and serving to actuate the shaft 46; a lever 50 supported on a pivot 50^a carried by the main frame and having its lower end connected pivotally with a movable bearing 50^b with which the shaft-section 45^a is equipped; and a cam-lever 51 actuated by a cam 52 on the shaft L^1 , the lever 51 being connected by a rod 53 to the upper end of the first shifting lever 50. A spring 54 serves to hold the cam-lever 51 against its cam. The cam is adapted to hold the friction disk 45^b either in neutral position, or in position against either one of the driving disks 47 and 48. Obviously, the mechanism is adapted to actuate the shaft 45 in either direction, and so to drive the sprocket-chains 40 first in one direction and then in the other direction.

35 Referring to Figs. 9, 10 and 12, each gripper 37 is carried by an adjustable arm 37^a which extends inwardly from the corresponding slide 38.

40 Beneath the path of each gripper 37 is a track 55 equipped with a cam-portion 55^a , at the rear end of which is a shoulder 55^b . These cam tracks are in the form of bars which extend across the space occupied by the rear conveyor B' , as shown in Fig. 15. The ends of the bars are adjustably connected with T-slots in transversely extending frame-members 9 and 56.

45 Referring to Figs. 10 and 12, each shaft or stem 37^a is equipped at its inner end with a fitting 37^b provided with a bore through which extends a longitudinally disposed stem 37^c which constitutes the shank of the main member of the gripper. This shank is adjustable in the fitting.

50 The gripper proper comprises a main jaw 37^d and a companion jaw 37^e pivotally connected with the main jaw at 37^f . A spring 37^g connects the jaws, and a plunger 37^h is 125 adapted to lift the upper jaw in the manner shown in Fig. 13. A spring-held cam-member or dog 37^i is pivotally connected with the lower jaw at the point 37^j . This member rides on the cam until it reaches the shoulder 130

55^b shown in Fig. 13, whereupon the member snaps over the shoulder and permits the jaw 37^e to close upon the cover. This action occurs after the operators have placed the 5 cover M' in position upon the feed-table M. Thereupon, the slides 38 are retracted and the cover is drawn forwardly to a position above the conveyors, as illustrated in Fig. 9.

10 The chains 40 are shown as extending through the tubular guides 39, the ends of the slides being connected to the guides at the point 57 (Fig. 12). In the illustration given, the cover-placing mechanism is adapted 15 to move the cover quickly from the feed-table to a position in which the front margin of the cover overlaps the rear portion of the pneumatic conveyor, the remaining portion of the cover being disposed above the auxiliary conveyor. This leaves the fabric disposed 20 with relation to the conveyor in a way which will be understood from Fig. 10. It will be noted, however, that only the front corners of the cover are supported by the grippers, so that the cover naturally will fall upon the bed, except at its front margin, as the cover 25 is moved forwardly.

In Fig. 1, the grippers 37 are shown at the rear end of their traverse, while in Fig. 30 17, they are shown at the front end of their traverse.

The fabric-forming mechanism O will be understood by reference to Sheets 1, 2, 4, 6, 9 and 10. As stated above, the forming mechanism is adapted to form pleats and intervening seam-ridges in the cover-piece. It is preferred to employ a series of pairs of longitudinally disposed formers which travel forwardly with the fabric, descend and rise again during the forward movement, and finally travel back to the rear end of their traverse by a straight-line movement while in elevated position.

Describing the pleat-forming mechanism O, it comprises a pair of slides 58 mounted on longitudinal guides 59 forming a part of a frame supported by hangers 60 depending from the frame parts A⁴, the suspended frame being equipped at its front portion with brackets 61 adjustably connected with a cross-bar 62 (Figs. 4 and 20) carried by the standards A³ of the main-frame; a pair of cross-heads 63 secured to the lower ends of plungers 64 which are vertically movable in guides 58^a with which the slides 58 are equipped; cross-rods 65 securely connecting together the cross-heads 63; a series of longitudinally disposed members 66 connecting the cross-shafts 65, each of the members 66 having fittings secured on the shafts 65, which fittings are provided with tubular vertical portions 66^a which afford guides; an intermediate pair of formers 67 carried by plungers 67^a which extend through the guides 66^a; additional pairs of formers 68, 69 and 70 the members of which are arranged

progressively on opposite sides of the intermediate formers, said additional formers being carried by vertical plungers 68^a, 69^a and 70^a; a pair of laterally positioned fabric engaging members 71 adapted to engage the lateral margins of the cover and hold the cloth moderately taut cross-wise of the bed during the gathering operation, the members 71 being shown in the form of felt rollers carried by freely movable plungers 71^a supported in the outermost members 66 which connect the cross-shafts 65; and sprocket-chains 72 which have their ends connected with the slides 58 and which pass about supporting rollers 73 with which the frame is equipped, it being noted that one length of each chain passes through the corresponding tubular guide 59.

The mechanism O comprises, further, a pair of cranks 74 (Figs. 4, 5 and 10) secured to shafts 74^a journaled in the slides 58 upon which are journaled pinions 74^b and upon which are fixedly secured disks 74^c which are adapted to be actuated by the pinions 74^b; fixedly secured racks 75 carried by the frame supported by the hangers 60 and the brackets 61, these racks being engaged by the pinions 74^b, which pinions are adapted to turn idly when the slides 58 move rearwardly, and are adapted to actuate the crank shafts 74^a when the slides 58 move forwardly; links 76 connecting the cranks 74 to the cross-heads 63 which support the pleat-formers; spring projected catches 77 mounted on the upper ends of the tubular guides 58^a, these catches being adapted to engage recesses 77^a in the cranks 74 so as to releasably hold the cranks in the standing position shown in Fig. 4, this being desirable during the rearward movement of the formers while they are in the elevated position; and a fixed projection 78 carried by the pinion 74^b which co-acts with a catch 79 carried by the disk 74^c, the catch or dog 79 being carried by a spring arm 80 which is secured to the disk 74^c, as shown in Figs. 7 and 8.

The mechanism O further comprises (Figs. 20, 22 and 23) a shaft 81 equipped with sprocket-wheels 82 which serve to actuate the sprocket-chains 72; grooved wheels 83 secured on the shaft 81, said wheels having connected therewith wires or chains 84 which support weights 85 which are adapted to turn the shaft 81 in such direction as to move the slides 58 to the rear end of their traverse; a tubular shaft 86 supported in a bearing 87 with which the frame is equipped, one end of said tubular shaft having secured thereto a sprocket-wheel 88 which is continuously actuated by a sprocket-chain 89 (Figs. 20 and 22); a ratchet-disk 86^a secured on the outer end of the tubular shaft 86; a crank-arm 81^a secured on the projecting end of the shaft 81; a pawl 90 in the form of a bell crank pivotally supported at 91 on the end

of the crank 81^a, said pawl having an actuating arm 90^a and a ratchet-engaging arm 90^b; a spring-held detent 92 mounted in the free end of the arm 90^a and engaging a stud 5 or projection 93 with which the crank-arm 81^a is equipped, it being understood that the detent 92 is adapted to releasably hold the pawl 90 in the position shown in Fig. 22.

The mechanism O further comprises a 10 spring-projected push rod 94, which, as shown in Fig. 22, is adapted to throw the pawl 90 to the ratchet-engaging position, the rod 94 being connected to a cam-lever 95 controlled by a cam 96 fixedly secured on 15 the shaft L¹¹; and a stop 97 disposed adjacent the face of the ratchet disk 86^a and adapted to engage the arm 90^a and effect release of the pawl 90 from the ratchet wheel at the proper moment. The stop 97 is 20 adjustably mounted on a bracket-member 98 carried by the frame.

From the description given, it will be understood that the ratchet-wheel 86^a rotates continuously with the tubular shaft 86; that when the cam 96 permits, the spring 99 will actuate the push-rod 94 and throw the pawl 90 to the ratchet-engaging position, whereupon the shaft 81 will turn with the ratchet wheel and will actuate the sprocket-chains 72 in a direction to advance the pleat-formers towards the front end of the machine. This action continues until the arm 90^a of the pawl engages the stop 97, whereupon the pawl is released from the ratchet wheel, and the shaft 81 is then rotated in the opposite direction by means of the weights 85, thus carrying the slides 58 to the rear end of their traverse.

In the forward movement of the slides 58, the rack-actuated pinions 74^b serve to actuate the disks 74^c and through the medium thereof to turn the crank-shafts 74^a, thus causing the cranks to lower the cross-heads 63 which are supported on the links 76. During this action, the plungers 64 move in the vertical guides 58^a (Fig. 4).

The descent of the cross-heads 63 continues during a portion of the advance movement of the slides 58 and during the final portion of the movement of the slides forwardly the crank arms again lift the cross-heads to the elevated position, where they are latched in a manner illustrated in Fig. 4. In the return movement of the slides 58, the cross-heads remain in an elevated position. The lower half of the path of formers, therefore, is of semi-elliptical form, while the upper half is a straight line.

As appears from Fig. 10, the plungers which carry the formers are equipped with springs 100, so that the plungers can yield when they reach the plane of the conveyor, while the cross-heads 63 continue to descend. It will be noted from Fig. 10 that the intermediate formers 67 are normally the lower

pair of formers, and that the members of the other pairs are normally located somewhat higher progressively, passing from the intermediate formers to the outer formers.

The effect is to cause the intermediate formers to engage the fabric first along linear portions of the fabric and depress portions of the fabric into the spaces between the intermediate ridge-bars. The other pairs of formers then progressively engage and depress the fabric into the spaces between the ridge-bars.

The members 71 are in the nature of wipers, or retarding devices, which engage the margins of the cover. These members are light members, gravity actuated, and normally they are about at the same level as the intermediate formers 67, so that the devices 71 will engage the lateral margins of the cover before the cover is withdrawn from the grasp of the grippers 37. Each gripper, as appears from Fig. 13, has its lower jaw provided with a socket in which is loosely mounted a ball 101, which is adapted to engage the fabric in opposition to the upper jaw. The ball serves the purpose of permitting the fabric to be withdrawn more readily laterally from the jaw as the gathering operation proceeds under the action of the pleat-formers. The pleat-formers, as noted above, bring the cover-fabric within the range of action of the suction-belt, by which the cover is then conveyed beneath and past the forming roll and sewing-mechanisms.

From the description given, it will be understood that the shaft L¹¹ is equipped with three cams. One of these cams (L¹²) controls the clutch L¹⁴, which in turn, controls the stopping of the rear batt-feeding rolls I and I' and the batt-conveyor Q'. The second cam (52) controls the shifting of the lever 50, which regulates the position of the shaft-section 45^a and therefore determines the direction of movement of the sprocket-chains 40 which reciprocate the grippers 37. The third cam (96) controls the coupling of the shaft 81 to the continuously rotating ratchet-wheel 86^a, and thus controls the movements of the sprocket-chains 72 which shift the slides 58 of the pleat-forming mechanism forwardly and rearwardly.

In view of the foregoing detailed description, the operation may be stated quite briefly:

The lining-fabric P is fed continuously through the machine and is creased to provide seam-ridges, which are well-defined at the point where the creasers G engage the lining and force it into the grooves of the forming-roll F; the strips of cotton-battling Q are carried forwardly by the endless conveyor Q', and are fed to the pleats by the main pair of batt-rolls H and H' and the auxiliary pair of feed-rolls I and I'; at proper intervals, the clutch L¹⁴ is released and

the operation of the auxiliary feed-rolls I and I' and of the conveyor Q' is stopped; the main feed-rolls H and H' continue to operate and cause the batts to be severed over the severing device J; the covers M' are placed, one at a time, on the feed-table M by two operators located at opposite sides of the table, the cover being properly positioned over the guide-pattern 31, with the front 10 margin of the cover projecting onto the supporting strips 33 and thus extending across the recesses 33^a; the grippers, properly timed, are moved rearwardly, the jaws open and seize the front corner-portions of the cover, 15 and the grippers are then quickly moved forwardly, carrying the cover to the left-hand position shown in Fig. 9; the slides 58 of the forming mechanism O are moved forward at the proper time, the pinions 74^b serving during the forward movement to actuate the crank-shafts 74^a, lower the cross-heads 63 to cause the formers to perform their function, and then raise the cross-heads. In the 20 return movement of the slides 58, the catches 25 78 slip past the spring-held catches 79. In other words, the rack actuated pinions 74^b turn idly during the rearward movement of the slides 58.

The covers are carried forward, seriatim, 30 from the feed-table, provided with pleats and intervening seam-ridges, and are then carried forward by the suction-conveyor, passing beneath the creasers G, beneath the forming-roll F, and beneath and past the 35 sewing-mechanisms. The upholstery then passes between the feed-rolls E and E', which may be usefully employed to insure the proper passage of the materials through the machine. On the other hand, these rolls may 40 be omitted, if desired.

The foregoing detailed description has been given for clearness of understanding only, and no unnecessary limitations should be understood therefrom, but the appended 45 claims should be construed as broadly as permissible in view of the prior art.

What I regard as new, and desire to secure by Letters Patent, is:

1. In upholstery manufacture, the method 50 of forming seam-ridges and intervening pleat-fullnesses in pre-cut covers which comprises: gripping the covers, seriatim, at their lateral edges, and carrying them forward, in 55 turn, over spaced ridges; depressing progressively parallel linear portions of the fabric into the spaces between the ridges; and pneumatically gripping the depressed portions and carrying the fabric forward 60 while the fabric is thus pneumatically held.

2. The method specified in claim 1, in 65 which the depressing of the parallel linear portions of the fabric is accomplished by downwardly and forwardly movable members which tend to aid in advancing the

fabric until it is brought fully within the pneumatic gripping action referred to.

3. In combination in a machine of the character set forth: a pneumatic conveyor and associated spaced ridges; a series of de- 70 pressible fabric-depressing members over the spaces between said ridges; and means operative to carry said members sequentially into position to bring successive linear portions of the fabric within the grip of said conveyor. 75

4. A machine as specified in claim 3, in which the fabric depressing members travel longitudinally with the fabric during the fabric-depressing action. 80

5. A machine as specified in claim 3, in which the fabric-depressing members are carried by a traveling frame which is lowered and raised while moving longitudinally of the conveyor, and in which the fabric-depressing members are independently movable with respect to the frame by which they are carried. 85

6. In combination in a machine of the character set forth: a bed comprising a conveyor and associated spaced ridges; a series of fabric-depressing members over the spaces between said ridges; and actuating means for said members adapted to bring them sequentially into position to depress linear portions of the fabric into the spaces between the ridges. 90

7. A machine as specified in claim 6, characterized by the cyclically moving frame upon which the fabric-depressing members are yieldingly mounted, the intermediate members being normally at one level and the flanking members being successively at higher levels. 95

8. A machine as specified in claim 6, in which the fabric-depressing members are carried by a cyclically moving frame which depends from longitudinally reciprocating slides equipped with means for lowering and raising said frame during the forward movement of the slides. 100

9. In a machine of the character set forth: a bed equipped with spaced longitudinal ridges and adapted to serve in forming a fabric into pleat-fullnesses and intervening seam-portions; longitudinally reciprocable slides mounted above said bed; and a cyclically moving frame mounted on said slides and equipped with fabric-depressing members disposed over the spaces between said ridges. 115

10. A machine as specified in claim 9, in which the fabric-depressing members comprise an intermediately positioned member or members disposed normally at one level, and flanking members disposed normally progressively at higher levels, said members being yieldingly held. 120

11. A machine as specified in claim 9, in which the cyclically traveling frame is equipped also with yieldingly mounted

- fabric-engaging members adapted to engage lateral marginal portions of the fabric.
12. In a machine of the character set forth: a bed comprising spaced longitudinal ridges over which a fabric may be shaped; a series of fabric-depressing members over the spaces between said ridges, the central member or members being normally at a given level and the flanking members being normally successively at higher levels; a pair of marginal fabric-engaging members adapted to press the marginal portions of the fabric against the bed; and means for cyclically carrying all of said members.
13. In combination in a machine of the character set forth: a bed comprising spaced longitudinally extending ridges over which a fabric may be shaped; a traveling fabric-placer adapted to advance fabrics seriatim over said bed; and a series of fabric-formers disposed over said bed and co-acting with said ridges.
14. A machine as specified in claim 13, in which a suction-conveyor is disposed beneath and associated with said ridges.
15. A machine as specified in claim 13, in which the fabric-placer comprises a pair of reciprocating slides mounted at the sides of the bed, and fabric-engaging devices adjustably connected with said slides.
16. A machine as specified in claim 13, in which the fabric-placer comprises a pair of reciprocating slides disposed at the sides of the bed, arms projecting inwardly from said slides, and grippers carried by said arms.
17. A machine as specified in claim 13, in which the fabric-placer comprises a pair of reciprocating slides mounted at the sides of the bed, grippers carried by said slides, and cam-devices adapted to open said grippers to permit them to grip the fabric.
18. A machine as specified in claim 13, in which the fabric-formers are yieldingly mounted on and depend from a cyclically moving frame, an intermediate former or formers being disposed normally at one level and the flanking formers being disposed normally at higher levels.
19. In a machine of the character set forth: a bed provided with spaced longitudinally disposed ridges over which a fabric may be shaped; and fabric-depressing mechanism comprising slides having cranks journaled therein, a cyclically moving frame carried by said cranks and equipped with yieldingly supported fabric-depressing members, guides on which said slides are mounted, racks associated with said guides, pinions journaled on the shafts of said cranks and engaging said racks, means for clutching the shafts of said cranks to said pinions when the pinions travel in one direction, a shaft and flexible transmission means connecting the same to said slides, and means for periodically turning said shaft in a direction to advance said slides and then in the opposite direction to retract said slides.
20. A machine as specified in claim 19, in which the last-mentioned shaft is actuated in one direction by a weight and actuated in the other direction by a continuously rotating ratchet device which is periodically connected to and then disconnected from said shaft.
21. A machine as specified in claim 19, in which the last-mentioned shaft is actuated in one direction by a weight and actuated in the other direction by a continuously rotating ratchet device which is periodically connected to and then disconnected from said shaft, said ratchet device comprising a continuously rotating ratchet wheel, an arm fixedly secured to the shaft, a pawl mounted on said arm and adapted to engage the ratchet wheel, and means for automatically throwing said pawl to the ratchet-engaging position and afterwards effecting release of the pawl to permit return of the shaft under the action of the weight.
22. In combination in a machine of the character set forth: a bed comprising a traveling conveyor and longitudinal stationary ridge-bars disposed above said conveyor; a cross-head disposed over the front portion of said conveyor; means for feeding a lining-fabric beneath said cross-head and forming seam-ridges in said fabric; means for placing a cover fabric over said bed; and a series of progressively acting fabric-formers disposed over the spaces between the ridge-bars.
23. In a machine of the character set forth: a bed provided with longitudinal ridges over which a fabric may be shaped; and fabric-blank placing mechanism comprising a fabric-blank supporting table; reciprocating slides at the sides of said bed; and fabric-blank engaging devices adapted to transfer fabric from said table to a position over said ridges.
24. Mechanism as specified in claim 23, in which the table is equipped at its front edge with recessed means for supporting the front margin of the fabric, and in which the fabric-blank engaging devices comprise grippers adapted to grip the fabric at said recesses.
25. Mechanism as specified in claim 23, in which the table is equipped at its front edge with recessed means for supporting the front margin of the fabric, and in which the fabric-blank engaging devices comprise grippers adapted to grip the fabric at said recesses and in which cam-devices are disposed at the sides of the bed and co-act with said grippers to open them to enable them to embrace the fabric.
26. Mechanism as specified in claim 23, in which the table is equipped at its front edge with recessed means for supporting the front margin of the fabric, and in which the fab-

ric-blank engaging devices comprise grippers adapted to grip the fabric at said recesses and in which cam-devices are disposed at the sides of the bed and co-act with said grippers to open them to enable them to embrace the fabric, said cam-devices being laterally adjustable over said bed.

27. In a machine of the character set forth: a bed comprising a suction-conveyor, a non-suction endless conveyor in the rear of the suction-conveyor, and spaced ridge-bars extending longitudinally over the conveyors; and fabric-depressing means normally disposed partially over both of said conveyors and comprising a series of progressively acting members disposed over the spaces between the ridge-bars and operating in sequence from the central portion of the bed laterally in both directions.

28. A machine as specified in claim 27, in which said fabric-depressing members depend yieldingly from a cyclically traveling frame adapted to advance with the conveyors and then return to starting position.

29. In combination in a machine of the character set forth: fabric-placing mechanism comprising reciprocating grippers; and a fabric-supporting table equipped with a guide-pattern and having at its front edge a projecting device for supporting the front margin of the fabric, said devices being recessed to permit the grippers to act to engage the fabric.

30. Means as specified in claim 29, in which the table is equipped also with a transparent plate beneath which the guide-pattern is disposed.

31. Means as specified in claim 29, in which the device for supporting the front margin of the fabric comprises recessed strips which are adjustable cross-wise of the table.

32. In fabric-forming mechanism: a bed provided with longitudinal ridges; reciprocable slides mounted at the sides of said bed and equipped with fabric-engaging means; sprocket-chains connected with said slides; a transverse shaft serving to actuate said chains; an actuating shaft for said first-mentioned shaft equipped with a swinging shaft-section provided with an actuating wheel; a continuously driven shaft equipped with driving wheels flanking said first-mentioned wheel; and a cam-control device controlling the position of said swinging shaft-section.

33. In combination in an upholstery-making machine: means for feeding a lining-fabric and creasing it to provide seam-ridges; a bed for shaping and feeding pre-cut covers, said bed being provided with longitudinal ridges; cover-placing mechanism for positioning covers, seriatim, over the bed; fabric-depressing mechanism disposed above and associated with said bed; batt-feeding means comprising main batt-feeding means adapted to feed batts to the pleats and aux-

iliary batt-feeding means in the rear of the main-feeding means; means for periodically stopping the action of the auxiliary batt-feeding means; and means for actuating the cover-placing mechanism and the fabric-depressing mechanism in timed relation with respect to the stopping of the action of said auxiliary batt-feeding means.

34. A machine as specified in claim 33, in which the cover-placing mechanism comprises grippers which serve to hold the front corners of the cover until after the fabric-depressing mechanism has begun to form the fabric, in which action the fabric is withdrawn from the grasp of the grippers.

35. A machine as specified in claim 33, in which the cover-placing mechanism comprises grippers which serve to hold the front corners of the cover until after the fabric-depressing mechanism has begun to form the fabric, in which action the fabric is withdrawn from the grasp of the grippers, and in which marginal fabric-engaging devices in the form of rollers co-act with the fabric-depressing mechanism.

36. In an upholstery-making machine: a bed equipped with ridges and intervening spaces over which a fabric may be formed; a series of shoes adjacent to and partially covering said ridges, said shoes having seam-ridge-forming portions rising therefrom, over and upon which a second fabric may pass and be formed, said portions being of progressively decreasing height from the intermediate portion of the bed laterally; a forming-device having grooves or spaces to accommodate portions of said shoes; and fabric-supporting means from which said second-mentioned fabric may be drawn over said shoes and beneath said forming-device.

37. In an upholstery machine a bed provided with devices upon which a fabric may be formed; a series of shoes supported on said bed having portions overlying and embracing said devices and having rearwardly inclined fabric-creasing portions of varying lengths; and a forming-device disposed over said bed having grooves into which the lower front portions of said shoes project.

38. In combination in a machine of the character set forth: a bed having stationary ridges over which a fabric may be shaped; a series of shoes disposed above said bed having horizontal portions recessed to loosely embrace said ridges and having inclined seam-ridge-forming portions of different lengths, the lengths decreasing progressively from the intermediate portion of the bed laterally in both directions; and a forming-device disposed above said bed having spaces into which the lower front portions of said shoes extend.

39. In an upholstery machine: a bed over which a fabric may be shaped; a forming-roll above said bed equipped with circumfer-

ential grooves and equipped also with toothed propelling members; and a series of shoes projecting into said grooves, over which shoes a fabric may be fed beneath the forming-roll.

5 40. A machine as specified in claim 39, in which the shoes are provided with inclined fabric engaging portions of varying lengths, decreasing from the intermediate portion of the bed laterally in both directions.

10 41. In upholstery manufacture, the method of forming seam-ridges and intervening pleat fullnesses in a fabric blank, which comprises disposing the fabric blank over spaced ridge bars and first forming at least one substantially complete longitudinal intermediate seam ridge over said ridge bars, and progressively forming seam ridges laterally in both directions therefrom.

20 42. The method specified in claim 41 characterized by progressively depressing fabric into the spacer between the ridge-bars and holding the fabric lightly stretched transversely across the ridges until the series of depressing actions has been initiated.

25 43. The method specified in claim 41, characterized by mechanically forcing the linear portions of the fabric between the ridges and then exerting a suction-grip thereon.

30 44. The method specified in claim 41 characterized by first placing the fabric blank in position where it is disposed wholly over the ridges and then exerting depressing actions successively to bring parallel linear portions of the fabric successively into the spaces between the ridges and within the gripping action of a suction-conveyor which advances the fabric blank.

40 45. In upholstery manufacture, the method of forming seam-ridges and intervening pleat fullnesses in a fabric blank, which comprises disposing the fabric blank over spaced ridge-bars and first depressing a complete intermediate pleat fullness between said ridge bars, and progressively forming complete pleat fullnesses laterally in both directions therefrom.

45 46. A method of forming pleats in upholstery material, which method comprises placing a fabric blank on a plurality of ridge bars, then forming pleat fullnesses in the material between said ridge bars in such man-

ner that the initial forming of at least one of said pleat fullnesses takes place before the initial forming of the others, and then sewing said fabric blank to a second fabric.

50 47. A method of forming pleats in upholstery material, which method comprises continuously advancing one fabric, intermittently placing fabric blanks in alignment with the first mentioned fabric, forming pleat fullnesses in said blanks, advancing said fabric blanks into predetermined relation with respect to said first mentioned fabric while said first mentioned fabric is being advanced, providing filling material between the first mentioned fabric and said fabric portions, and sewing said fabric blanks to the first mentioned fabric.

55 48. A method of forming pleats in upholstery material, which method comprises placing a fabric blank in a predetermined position, initially forming at least one pleat fullness extending the entire length of said fabric blank and then forming additional pleat fullnesses extending the entire length of the fabric blank.

60 49. A method of forming pleats in upholstery material, which method comprises placing a fabric blank in a predetermined position, forming pleats in it while it is in said position, advancing a second fabric, advancing said fabric-blank, feeding filling material between said fabrics, and then sewing said fabrics to each other.

65 50. A method of manufacturing cushions which comprises: forming fabric-blanks in succession to provide the same with pleat-fullnesses and intervening seam-portions and bringing said pleat-fullnesses within the grip of a suction-conveyor which serves to advance the formed blanks; feeding a continuous fabric so that it contacts with the seam-portions of said formed blanks in succession; and sewing the seam-portions of each blank to the continuous fabric while the fabrics move in unison gripped by said suction-conveyor.

70 51. A method of manufacturing cushions as specified in claim 50, supplemented by feeding strips of batts to said pleat-fullnesses.

ALLISTER S. MITCHELL.
